UNITED STATES PATENT OFFICE.

GEORGE M. HUBBARD, OF NEW HAVEN, CONNECTICUT, ASSIGNOR TO THE
W. & E. T. FITCH COMPANY, OF SAME PLACE.

DESIGN FOR A SNAP-HOOK.

SPECIFICATION forming part of Design No. 28,065, dated December 21, 1897.

Application filed October 18, 1897. Serial No. 655,636. Term of patent 14 years.

To all whom it may concern:

Be it known that I, GEORGE M. HUBBARD, of New Haven, in the county of New Haven and State of Connecticut, have invented a
5 new Design for a Snap-Hook; and I do hereby declare the following, when taken in connection with the accompanying drawings and the letters of reference marked thereon, to be a full, clear, and exact description of the
10 same, and which said drawings constitute part of this specification, and represent, in—

Figure 1, a top view of the body of a snap-hook embodying my design; Fig. 2, a view, partially in section, illustrating the essential
15 feature of my design.

This invention relates to a design for a snap-hook; and the design consists in the formation of the body of the hook, as hereinafter described, and shown in the accompanying
20 illustrations.

As herein shown, the body A of the hook is characterized by having the walls of the recess B at the rear end extend inward, forming flanges C, which extend over said recess, and having the outer surfaces of said side 25 walls or flanges rounded or merged into each other, as shown in the accompanying illustrations.

I claim—

The design for a snap-hook as herein shown 30 and described.

In testimony whereof I have signed this specification in the presence of two subscribing witnesses.

GEORGE M. HUBBARD.
